UNITED STATES PATENT OFFICE.

ROBERT E. EINSTEIN, OF ST. LOUIS, MISSOURI, ASSIGNOR TO AMERICAN FLANGE FROG AND RAILWAY IMPROVEMENT COMPANY, OF ST. LOUIS, MISSOURI, A CORPORATION OF FLORIDA.

FLANGE FROG.

Application filed October 12, 1923. Serial No. 668,122.

To all whom it may concern:

Be it known that I, ROBERT E. EINSTEIN, a citizen of the United States, residing at St. Louis, Missouri, have invented a certain 5 new and useful Improvement in Flange Frogs, of which the following is a full, clear, and exact description, such as will enable others skilled in the art to which it appertains to make and use the same.

10 This invention relates to railway frogs of the type known commercially as "flange frogs," and particularly flange frogs of the kind in which the guard members consist of removable elements that are detachably connected to the main body of the frog.

One object of my present invention is to provide a flange frog of the general type mentioned, which is of such construction that the guard members can be easily combined 20 with the main body of the frog, either in the operation of manufacturing the complete frog, or when the main body of the frog is installed in a track.

Another object is to provide a flange frog 25 of the type referred to in which the guard members are supported by the track ties and are equipped with portions on which the main body of the frog rests.

Another object is to provide a flange frog 30 of the kind just referred to in which the guard members are combined with the main body of the frog in such a way that the strains to which the guard members are subjected when wheels travel over the frog tend 35 to counteract the downward pressure exerted on the main body of the frog by said wheels.

And still another object is to provide a 40 multiple part frog whose elements are combined in such a way that the frog can be kept rigid and solid with minimum trouble and expense. Other objects and desirable features of my invention will be hereinafter pointed out.

45 Figure 1 of the drawings is a top plan view of a flange frog constructed in accordance with my invention.

Figure 2 is a side elevational view of said frog.

50 Figure 3 is a transverse sectional view, taken on the line 3—3 of Figure 1.

Figure 4 is a horizontal sectional view, taken on the line 4—4 of Figure 3.

55 Figure 5 is a transverse sectional view, taken on the line 5—5 of Figure 1; and

Figure 6 is a transverse sectional view, taken on the line 6—6 of Figure 1, looking to the right or towards the point of the frog.

Referring to the drawings which illustrate the preferred form of my invention, A designates the point of the frog, B designates the running surfaces on which the treads of the wheels travel in passing over the frog, and C designates guard members that are used to guide the flange of a passing wheel past the point of the frog by engaging the tread rim of the wheel in a horizontal plane above the running surfaces of the frog. The body portion of the frog comprising the point A and the running surfaces B, may consist of a cast structure, or it may consist of a built up structure formed from conventional T rails. In the form of my invention herein illustrated the point A is formed by two T rails, the running surfaces B are formed by two wing rails, and the guard members C consist of castings constructed of steel or some suitable steel alloy. Said guard members C are arranged at opposite sides of the wing rails that constitute the running surfaces B of the frog, and each of said guard members is provided with a wheel tread surface 1 that lies in the same horizontal plane as the adjacent running surface B of the frog, and an upwardly-projecting wheel rim engaging portion 2 that extends longitudinally of the frog so that it will co-operate with the rim of a passing wheel to guide the flange of the wheel properly past the point A of the frog.

Instead of mounting the guard members C on the main body portion of the frog or on a supporting plate on which the main body portion of the frog rests, as has heretofore been the usual practice, I construct 95 the guard members C in such a way that they will bear directly on the track ties, and the main body portion of the frog will rest or bear upon portions on said guard members. Any suitable means can be used for connecting the main body of the frog with the guard members C, but I prefer to construct the guard members in such a way that they can be drawn into snug engagement with the main body portion of the frog by one or more wedge-shaped devices 100 inserted between co-operating portions on said guard members and main body and then securely clamp said elements together by bolts or other suitable fastening devices 110

that are arranged transversely of the structure.

This method of connecting the co-operating parts of the frog together makes it possible to maintain the frog in a rigid and solid condition with minimum trouble and expense and it greatly simplifies the operation of connecting the parts of the frog together during the process of manufacturing the frog, or when it becomes necessary to renew any part of the frog after it has been installed in the track. Each of the guard members C is provided with a tie engaging portion or base portion 3 that rests upon the ties of the track and which is used to support the main body of the frog. The particular shape and dimensions of said base portion 3 are immaterial, but in most instances it will consist of a horizontally-disposed web that is provided with laterally-projecting extensions 3^a arranged in alignment with the track ties, so as to provide a bearing surface of sufficient area to firmly support the guard members C and the main body portion of the frog which said guard members carry. The laterally-projecting extensions 3^a at the outer sides of the guard member C are provided with holes 3^b through which spikes can be inserted so as to securely connect the guard members to the track ties, and the extensions 3^a at the inner sides of the guard members terminate at a point near the center line or longitudinal axis of the frog. While various means may be used to connect the guard members C to the main body portion of the frog without departing from the spirit of my invention, I prefer to provide the base portions or tie engaging portions 3 of the guard members C with devices that are adapted to co-operate with wedge-shaped filler blocks E and F interposed between the wing rails B to draw said guard members into snug engagement with the wing rails. As shown in Figure 3, the laterally-projecting extensions 3^a of the base portions 3 of the guard members that are located in advance of the point of the frog are provided with upwardly-projecting ribs 4 that have inclined faces, indicated by the reference character 4^a in Figure 4, which extend at an angle to the center line or longitudinal axis of the frog. The filler block E that is arranged between the wing rails B at this part of the frog is wedge-shaped in general outline and is provided on its underside with a wedge-shaped groove 40 that receives said ribs 4, said groove 40 being tapered oppositely to the bevel of the filler block. Accordingly, when the filler block E is moved longitudinally of the frog towards the frog point A, the side faces of said block will exert pressure on the wing rails in a direction to move them outwardly or laterally against the guard members C, and the side walls of the groove 40 in the underside

of said filler block that receives the ribs 4 on the base portions 3 of the guard members will exert pressure on the guard members in a direction tending to draw them inwardly into snug engagement with the wing rails. After the filler block E has been driven in a direction to draw the guard members into snug engagement with the wing rails, said parts are clamped together by bolts 5 arranged transversely of same, as shown in Figure 3, the side portions of the filler block having elongated holes designated by the reference character 5^a in Figure 4, so as to provide for the longitudinal movement of said filler block with relation to the wing rails. The filler block F that is arranged at the throat of the frog is also wedge-shaped and provided on its underside with a wedge-shaped groove that receives inclined or angularly-disposed, upwardly-projecting ribs 4 on the base portions 3 of the guard members, the guard members, wing rails and filler block F being securely clamped together by through bolts 6 that are arranged transversely of said elements. The wing rails are held in spaced relation with the point A of the frog by means of the filler blocks G arranged between the web of the frog point and the wing rails and clamped to said elements by through bolts 7 that also pass through the guard members C.

A flange frog of the above construction is easy to assemble in the operation of manufacturing the frog and the guard members or main body portion of the frog can be removed easily for replacement or repair after the frog has been installed in a track. Owing to the fact that the frog comprises wedge-shaped elements, which, when driven in one direction, cause the guard members to be drawn into snug engagement with the main body part of the frog, it is a comparatively simple matter to keep the frog perfectly solid and rigid, thereby materially reducing the cost of maintenance of flange frogs of the kind in which the guard members consist of elements separate and distinct from the main body portion of the frog. The base portions of the guard members C provide a firm and rigid support or bearing for the frog on the ties of the track, and as the main body portion of the frog comprising the point and the running surfaces are carried by base portions of the guard members that are arranged near the center line of the frog, the lateral strains exerted on the rim engaging portions 2 of the guard members C by wheels passing over the frog tend to counteract the downward loads exerted on the running surfaces by said wheels.

Having thus described my invention, what I claim as new and desire to secure by Letters Patent is:

1. A flange frog, comprising a main body portion composed of a point and running

surfaces, and guard members formed by elements separate and distinct from the main body of the frog and arranged so as to support said main body portion.

5. 2. A flange frog, comprising separate guard members adapted to be connected to the ties of the track, and a main body portion comprising a point and running surfaces carried by and detachably connected 10 to said guard members.

15. 3. A flange frog provided with a point, a running surface, a guard member detachably combined with said elements and provided with a wheel rim engaging portion arranged in a higher horizontal plane than said running surface, and means on 20 said guard member that supports and carries said point and running surface.

25. 4. A flange frog, comprising a main body portion composed of a point and running surfaces, separate guard members having supporting portions on which the main body portion of the frog is removably mounted and wheel rim engaging portions on said 30 guard members arranged in a higher horizontal plane than the running surfaces of the frog.

35. 5. A flange frog having a main body portion comprising a point and running surfaces, guard members that support said main body portion, and wedge-shaped devices for drawing said guard members into snug engagement with said main body portion.

40. 6. A flange frog having a main body portion comprising a point and running surfaces, and guard members arranged at opposite sides of said main body portion and provided with tie-engaging portions that extend under said main body portion so as to form a support on which said body portion is removably mounted.

45. 7. A flange frog having a main body portion comprising a point and running surfaces, guard members arranged at opposite sides of said main body portion and provided with tie-engaging portions that extend under said main body portion and support the same, and a wedge-shaped device adapted to co-operate with said elements to draw them into snug engagement with each other.

55. 8. A flange frog, comprising a point, wing rails, guard members provided with portions on which said wing rails rest, and a wedge-shaped device interposed between said wing rails and adapted to co-operate with parts on the wing rail supporting portions of said guard members for drawing 60 the guard members into snug engagement with the wing rails.

65. 9. A flange frog composed of a main body portion that comprises a point and running surfaces, guard members arranged at opposite sides of said main body portion, an

adjustable means for drawing said guard members into snug engagement with said main body portion, and means for securely clamping said elements together.

10. A flange frog composed of a main body portion comprising a point and running surfaces, guard members arranged at opposite sides of said body portion and formed by elements separate and distinct from said body portion, and tie-engaging 70 portions extending laterally in opposite directions from each of said guard members that form a support on which the main body portion of the frog is removably mounted and also provide a substantial bearing surface for said guard members on the track ties.

11. In a flange frog, a part that constitutes a running surface for a wheel passing over a frog, a guard member arranged at one side of said part and provided with a wheel rim engaging portion arranged in a higher horizontal plane than said running surface, an integral base portion on said guard member on which said part is supported, and an 80 adjustable device for drawing said guard member into snug engagement with said part.

12. In a flange frog, a part that constitutes a running surface for a wheel passing over the frog, a guard member arranged at one side of said part and provided with a wheel rim engaging portion arranged in a higher horizontal plane than said running surface, a base portion on said guard member on which said part is supported, and a wedge-shaped device interposed between said part and a rib on said base portion for drawing said guard member into snug engagement with said part.

13. A flange frog, comprising parts that constitute running surfaces for wheels which travel over the frog, guard members arranged at opposite sides of said parts, base portions on said guard members on which said parts rest, a wedge-shaped filler block interposed between said parts, and co-operating means on said filler block and on the base portions of said guard members for drawing said guard members into snug engagement with said parts when said filler block is moved longitudinally in one direction.

14. In a flange frog, parts that constitute running surfaces of the frog, guard members arranged at opposite sides of said parts and provided with wheel rim engaging portions arranged in a higher horizontal plane than the running surfaces of the frog, base portions on said guard members on which said parts rest, a wedge-shaped filler block interposed between said parts and provided on its underside with a tapered groove, and ribs on said base portions that enter said groove, for the purpose described.

15. A flange frog, comprising a point, wing rails, guard members at opposite sides of the wing rails provided with base portions that support the wing rails and the point of
5 the frog, filler blocks interposed between the wing rails, and co-operating means on said filler blocks and on the base portions of the guard members for drawing the guard members into snug engagement with the
10 wing rails.
16. A flange frog, comprising a point, wing rails, guard members at opposite sides of the wing rails provided with wheel rim engaging portions arranged in a higher horizontal plane than the top sides of said wing rails, base portions on said guard members on which the wing rails and frog point are supported, wedge-shaped filler blocks interposed between the wing rails and provided
15 on their undersides with tapered grooves, and
20 ribs on the base portions of the guard members that project into said grooves, for the purpose described.
17. A flange frog having a main body portion comprising a point and parts that constitute the running surfaces of the frog, guard members arranged at opposite sides of said main body portion and provided with wheel rim engaging portions arranged in a higher horizontal plane than the running
25 surfaces of the frog, base portions on said guard members on which the body portion of the frog is supported, means adapted to be adjusted longitudinally of the frog for exerting a wedging action on the guard members so as to draw them into snug engagement with the main body portion of the frog, and means for clamping the guard members to said main body portion.
